UNITED STATES PATENT OFFICE

2,077,199

ELECTRIC LAMP

Heinrich Asmussen, Berlin-Steglitz, Germany,
assignor to General Electric Company, a corporation of New York

Application August 21, 1936, Serial No. 97,263
In Germany August 29, 1935

2 Claims. (Cl. 176—32)

My invention relates to electric lamps and similar devices comprising a bulb having an electrical energy translation element such as a filament sealed therein and a base mounted on said bulb. More particularly, my invention relates to bases for said devices and still more particularly to so-called mechanical bases in which the usual cement which unites the base to the glass bulb is eliminated.

0 Mechanical bases have been proposed in which the base is held on the bulb solely by means of a leading-in wire of high tensile strength and is prevented from turning by corresponding engagement means in the base and bulb. The 5 leading-in wire is stretched tightly between the usual stem press of the lamp and the base and is attached to the latter, preferably by solder. One or more longitudinal grooves in the neck of the bulb and indentations in the base shell provide the engagement means for preventing rotation of these parts. A mechanical base of this construction is shown in my Patent 2,014,220, which issued September 10, 1935. With this construction, the base and bulb neck must correspond in size so closely that there is no play 10 therebetween and the base shell slides on the bulb neck; otherwise, a slight back and forth lateral movement or wobble of the base is possible. However, the occurring friction makes it quite difficult to slide the base onto the bulb at assembly when these parts fit properly, and many lamps are broken. For this reason, it has been customary to permit a certain amount of play between the base and bulb neck, which has 15 35 the disadvantages already referred to.

To prevent the base from wobbling, a thin filling medium—preferably a layer of shellac—is placed between the inner surface of the base and the neck of the bulb. The shellac is placed 20 either on the inner surface of the base or better still on the neck of the bulb as it lubricates and facilitates mounting the base. An alcoholic shellac solution is preferably used, which leaves a very thin layer of shellac when the alcohol evaporates, as this is sufficient to compensate for the small difference in dimensions and fills completely the narrow gap between the base and the bulb.

50 The thin layer of shellac is in addition a binding medium but does not in any way constitute a substitute for cement for the adhesive qualities of the shellac layer are slight compared to those of cement and, on the other hand, there is very 55 much less shellac than cement used. The addi-

tion of the shellac does not reduce the advantages of the mechanical base which in itself provides for the elimination of the heating operation normally used to cause the basing cement to harden and all other disadvantages traceable 5 to the basing cement.

In the drawing, Fig. 1 is an elevation partially in section of an incandescent lamp having a mechanical base of my invention; Fig. 2 is a side elevation of the base at right angles to Fig. 1; 10 and Figs. 3 and 4 are a section through and a side elevation at right angles thereto respectively of a modified mechanical base of my invention.

In Fig. 1, the incandescent lamp is comprised of a bulb 10 having a filament 11 sealed therein 15 and attached to the inner ends of the leading-in wires 12 and 13. The leading-in wires 12 and 13 pass through the stem press portion 14 of the stem tube 15 which supports the mid-portion of the filament 11 through the arbor 16 and the support wires 17. The neck portion 18 of the bulb 10 is formed particularly for the mechanical base 19 and is provided with a neck portion 20 which fits into the threaded shell 21 thereof and with a pair of oppositely disposed grooves 22 20 which register with indentations 23 (Figs. 1 and 2) in the said shell 21. The base 19 is comprised of the shell 21, the metal eyelet 24 and the insulation 25 and is slipped over the neck portion 20 of the bulb 10 after it is first coated with a light alcohol and shellac solution. The alcohol evaporates, leaving the thin shellac layer 26 only a few fractions of a millimeter in thickness which fills in between the base shell 21 and the bulb neck 20 so that the base 19 can not wobble. One 30 35 of the leading-in wires 12 is bent back into one of the grooves 22 and under the rim of the base shell 21 and is soldered or welded thereto in the indentation 23. The other of said leading-in wires 13, which is particularly strong, passes 40 through a central hole in the insulation 25 and the eyelet 24 and is either soldered or welded to said eyelet 24.

In the species of my invention shown in Figs. 3 and 4, the neck portion 27 of the bulb is formed 45 into the screw threads 28 and the boss 29. The screw threads 28 support the lamp when they are screwed into the so-called standard socket. The boss 29 supports the base 30 which is comprised of the metal shell 31, the insulation 32 and the eyelet 33. As in the previous instance, the shell 31 is indented at two oppositely disposed points 34 which register with longitudinal grooves in the boss 29 and prevent the base 30 from turning. In this case, the shell 31 is made to fit 50 55

snugly onto the lamp by a layer 35 of shellac placed on the inner surface of the said shell 31 in such a position as to engage the boss 29. The leading-in wires 12 and 13 are attached to the shell 31 and the eyelet 33 respectively of the base 30 which is held in place on the lamp by the strength of leading-in wire 13 as disclosed in my patent hereinbefore referred to.

What I claim as new and desire to secure by Letters Patent of the United States is:

1. An electric device comprising a bulb having a neck portion and a base comprising a metal shell surrounding at least a portion of the bulb neck and an end eyelet, said bulb neck and base shell having interlocking engagement means therein for preventing relative rotation therebetween, a filling medium between said bulb neck and said base shell for preventing the base from wabbling, and a leading-in wire having a portion thereof sealed in a portion of the bulb and an end thereof secured fixedly to said base

end eyelet, said leading-in wire being tightly stretched between said bulb and base and constituting the sole means for holding said base firmly on said bulb neck against longitudinal displacement.

2. An electric device comprising a bulb having a neck portion and a base comprising a metal shell surrounding at least a portion of the bulb neck and an end eyelet, said bulb neck and base shell having interlocking engagement means therein for preventing relative rotation therebetween, a layer of shellac between said bulb neck and said base shell for preventing the base from wabbling, and a leading-in wire having a portion thereof sealed in a portion of the bulb and an end thereof secured fixedly to said base end eyelet, said leading-in wire being tightly stretched between said bulb and base and constituting the sole means for holding said base firmly on said bulb neck against longitudinal displacement.

HEINRICH ASMUSSEN.
